PLIERS

Charles S. Butler, Mansfield, Ohio

Application March 23, 1938, Serial No. 197,695

2 Claims. (Cl. 81—5.1)

This invention relates to pliers and has for an object to provide a special tool for applying and removing a gasket of the type known as the "gold head."

5 A further object is to provide a tool of this character which will be formed of a few strong simple and durable parts, which will be inexpensive to manufacture and which will not easily get out of order.

10 With the above and other objects in view the invention consists of certain novel details of construction and combinations of parts hereinafter fully described and claimed, it being understood that various modifications may be resorted to

15 within the scope of the appended claims without departing from the spirit or sacrificing any of the advantages of the invention.

In the accompanying drawing forming part of this specification

20 Figure 1 is a front elevation of the pliers constructed in accordance with the invention and showing the same applied to a gasket of the "gold head" type.

Figure 2 is a longitudinal sectional view of the 25 pliers taken on the line 2—2 of Figure 1.

Referring now to the drawing in which like characters of reference designate similar parts in the various views, 10 designates a pair of handles which are pivotally connected together near their front ends by a pivot pin 11, and terminate at their front ends in hooks 12 which are adapted to engage the arched shouldered spring 13 of a gasket 14 of the "gold head" type, this type of gasket having a bar 15 terminating in aligned ends 16 which enter sockets 17 formed at diametrically opposite points on the inner surface of the gasket.

30 A pair of bars 18 are slidably mounted on the pivot pin 11 and project beyond the jaws 12, there being slots 19 in the bars receiving the pivot pin 11. The bars are connected together in spaced relation at the front end by a rivet 20 which is provided with a uniformly enlarged central portion 21 to hold the bars spaced apart. One 35 of the bars is longer than the other and projects beyond the rivet while the enlarged central portion of the rivet is provided with a recess 22. The projecting end of the long bar and the recess 22 form a seat to receive the central portion of the spring 13 of the gasket substantially midway between the two hooks 12.

The opposite ends of the bars 18 are secured to a pivot pin 23 and a pair of links 24 are pivotally connected to the pivot pin 23 at one end

and at the opposite end are pivotally connected to the respective handles 10 by pivot pins 25.

To insert or remove the gasket 14 the center of the spring 13 is seated in the seat formed by the projecting end of the long bar 18 and the 5 groove 22 in the rivet 20 and the hooks 12 are engaged on the spring at opposite sides of the center of the spring.

When the handles 10 are moved toward each other the links 24 will move the bars 18 to deform 10 the center of the spring while simultaneously the hooks 12 will be moved toward each other to compress the spring sufficiently to permit the shoulders 26 of the spring to pass the stop shoulders 27 of the steam head 28 or other pipe. In this 15 position of the spring the gasket may be inserted or removed. When the gasket is inserted the handles 10 are spread apart and this movement of the handles withdraws the bars 18 longitudinally from the spring and at the same time 20 moves the hooks 12 outwardly to permit the spring to expand and lodge the shoulders 26 against the stop shoulders 27 of the steam head 28.

From the above description it is thought that the construction and operation of the invention 25 will be fully understood without further explanation.

What is claimed is:

1. Pliers for applying or removing a gasket of the type having a shouldered arch spring for engaging an internal stop shoulder and securing the gasket in a pipe, comprising crossed handles pivotally connected together at their crossing, hooks formed on the front ends of the handles adapted to engage the spring of the gasket at opposite 30 sides of the center of the spring, a bar slidably mounted on the pivot of the handles and having its front end projecting beyond the jaws and recessed to engage the center of the arch spring when the jaws engage the sides of the springs 35 near the shoulders thereof, and links connecting the rear end of the bar to the handles and adapted to extend the bar when the handles are closed together to deform the center of the spring longitudinally while the hooks simultaneously move 40 toward each other to deform the sides of the spring toward each other above the shoulders thereof.

2. Pliers for applying or removing a gasket of the type having a shouldered arch spring for 50 engaging an internal stop shoulder and securing the gasket in a pipe, comprising crossed handles, a pivot pin connecting the handles together at their intersection near their front ends, hooks formed on the front ends of the handles adapted 55

to engage the spring of the gasket at opposite sides of the center of the spring, a bar extending between the handles and projecting beyond the ends of the jaw, said bar having a longitudinal slot, said pivot pin passing through said slot, means on the front end of the bar for engaging the spring at the center thereof when said hooks are engaged with the opposite sides of the spring intermediate the center and the shoulders of the 5 spring, and links pivotally connected to the rear

end of the link and pivotally connected to the handles and adapted to move the bar forwardly when the handles are closed together to deform the spring at the center thereof while the hooks simultaneously deform the spring at the sides 5 thereof to contract the spring in such manner that the shoulders of the spring may pass the shoulders of the pipe.

CHARLES S. BUTLER. 10
